(57) **CLAIM**

We claim the ornamental design for a syringe cap for sealing syringe for medical purpose, as shown and described.

DESCRIPTION

FIG. 1 a right side view of a syringe cap of the new design. FIG. 2 is a rear view of the syringe cap of FIG. 1. FIG. 3 is a left side view of the syringe cap of FIG. 1. FIG. 4 is a front view of the syringe cap of FIG. 1. FIG. 5 is a top view of the syringe cap of FIG. 1. FIG. 6 is bottom view of the syringe cap of FIG. 1. FIG. 7 is perspective top view of the syringe cap of FIG. 1. FIG. 8 is a perspective bottom view of the syringe cap of FIG. 1; and, FIG. 9 is a rear view of the syringe cap of FIG. 1, showing the cap mounted on a cartridge (shown in dashed lines). The dashed lines depict environmental aspects and form no part of the claimed design.
